Specification of Letters Patent.

Patented Apr. 9, 1918.

Application filed June 26, 1917. Serial No. 177,070.

To all whom it may concern:

Be it known that I, EDWIN HANSALPAKAR, citizen of the United States, residing at Randolph, in the county of Norfolk and 5 State of Massachusetts, have invented new and useful Improvements in Heel-Presses, of which the following is a specification.

This invention relates to the art of building heels for boots and shoes. By "heels" 10 in this connection is meant the blocks or blanks made from lifts of leather, leather-board, or other suitable material united together, which are furnished to shoemakers to be applied to shoes in the making, and 15 thereafter trimmed and otherwise finished. Such heels are made by laying lifts which have been coated with adhesive one upon another in a pile to the required height, this operation being usually called "building" 20 the heel, and then generally driving a nail, or several nails, through the pile to retain the lifts in their alinement until the adhesive has become firm and hard. The particular 25 purpose of the invention is to furnish a machine in which the heels thus built may be placed as soon as completed, and by which the heels may be held confined under pressure while the adhesive is drying or setting.

This necessary part of the process of making merchantable heels has hitherto generally been performed in the following manner:—The operator who builds the heels places them one by one, as soon as completed, 30 on a board until all the available space on 35 the board is occupied. Then the operator lays a second board on top of the heels so placed and proceeds as before filling the boards with heels and placing boards to be filled on the tier of heels last completed. 40 When the stack of boards with heels so placed upon them has become great enough for economical handling, an attendant carries it to a press and assembles such stack with others and then applies pressure to the 45 top of the stack by means of jack screws or equivalent pressure applying mechanism with which such presses are provided. Such pressure applying mechanisms are usually operated manually, the 50 operator applying all his strength to the lever or handle of the mechanism. After

a pile or stack of heels has remained under pressure for a certain time the heels shrink somewhat owing to the evaporation of the liquid in the adhesive which the lifts 55 have previously absorbed and which has caused them to swell. In consequence of this shrinkage the pressure previously applied is more or less relaxed and it then becomes necessary for the operator of the press to set 60 up the screws again to take up the slack caused by such shrinkage. Then the heels remain in the press for a length of time sufficient to enable the adhesive to become thoroughly set, this length of time being dependent 65 on the character of the adhesive used and ordinarily being a matter of several hours. After that the heel blanks are allowed to dry further for several hours in a place provided for the purpose, called the drying room, 70 where the air is kept warm and dry, whereupon they are ready to be compressed into finished merchantable heels to be furnished to shoe manufacturers.

There are several objectionable features 75 about the common method of pressing heel blanks above briefly outlined, among which are included the following:

First. The presses are bulky and occupy 80 much valuable floor space. This is particularly true in large factories where great quantities of heels are made and in which there must be a correspondingly large number of presses.

Second. The heels are not put under pressure immediately upon being built up, but wait until enough heels have been accumulated to fill a press. Most heels are not put in the press until many minutes and sometimes an hour or more after being built, 85 during which time they stand beside the building operator's bench until enough have accumulated to make it economically feasible to put the heels in the press. During this waiting period the adhesive becomes 90 partially dry or set, and the individual lifts of the blanks, partially dry, have a tendency frequently to warp and thus separate from one another. When the heels in this partly dried condition are put in the press and subjected 95 to pressure the relation of the lifts to one another is violently changed and the 100

bond created by the partially set adhesive is broken. The adhesive having thus lost some of its strength is no longer as efficient as before and thus does not bind the lifts 5 together after being put under pressure so firmly or so completely as it would have done if the blanks had been put in the press as soon as made.

Third. Pressure applied as before described in the press is not uniform in all presses and upon all heels because it depends upon variable factors, among which are the strength and temporary physical condition of the operator who sets up the 10 screws of the press, the mechanical efficiency of the jack screws or other pressure applying mechanism, and the condition of the press itself, that is, whether it is in good working order, or in bad working order so 15 that much or little of the power applied is lost in overcoming friction.

Fourth. The delays and expense incident to the method used of collecting piles of heels from the operator who builds them 20 and carrying them to the presses.

Fifth. The length of time required for the heels to pass to the press, the time they remain in the press and the subsequent time they remain in the drying room, which 25 makes the proportion of heels in process of construction to completed heels unduly large.

Sixth. After removal of the heels from the press the boards must be separated from the heel blanks and returned to the operators. This is a service which is the cause 30 of additional expense.

The object of my invention is to do away with all of the objectionable features hereinbefore pointed out and to furnish a press- 35 ing means which does not occupy any space which would otherwise be available for other uses, in which the heels may be placed by the operator as soon as completed and automatically put under pressure, in which the 40 pressure thus supplied is uniform upon all heels, in which the heels are so ventilated that they are so far dried as not to be required to be placed in the drying room before being compressed into merchantable 45 heels ready for application to shoes, and by which the boards are automatically separated from the heels and returned to the operator ready to be again filled with new 50 heels.

55 The means by which I accomplish the foregoing objects, in which my invention consists, are set forth in the following specification and pointed out in the claims in connection with the detailed description of 60 a specific apparatus embodying the invention. The drawings forming a part of this apparatus represent the particular machine thus described and presented for the purpose of illustrating the invention, but without intent to limit the same to such specific

machine otherwise than appears from the terms of the claims.

Figure 1 of the drawings is a front elevation of the machine referred to.

Fig. 2 is a partial section on line 2—2 of 70 Fig. 1 and an elevation of the parts of the machine at the left of such line.

Fig. 3 is an elevation of the right hand side of the machine.

Fig. 4 is a vertical cross section taken 75 approximately on line 4—4 of Fig. 1.

Figs. 5 and 6 are detail sectional views of parts of the opposite side frames of the machine.

Fig. 17 is a sectional view on line 17—17 of Fig. 16.

Fig. 18 is a cross sectional view of the 110 press taken on line 18—18 of Fig. 4.

Fig. 19 is a sectional view taken on line 115 19—19 of Fig. 18.

Fig. 20 is a plan view of parts below the 115 line 20—20 on Fig. 1.

Fig. 21 is a detail of the main driving gear and the pulley therefor.

Fig. 22 is an elevation and part section on line 22—22 of Fig. 21.

Fig. 23 is a view of the parts shown at 120 the right hand side of Fig. 21 but occupying a different position from that illustrated in the latter figure.

Fig. 24 is a sectional elevation on line 125 24—24 of Fig. 23 and of the parts at the right of said line.

Fig. 25 is a complete plan view of the machine, being on a smaller scale than Fig. 13 and showing parts not shown in the latter figure.

Fig. 26 is a vertical section on line 26—26 of Fig. 25 showing only the upper part of the machine.

Fig. 27 is a plan view of parts below the line 27—27 of Fig. 26.

Fig. 28 is a plan view similar to Fig. 25, but showing the movable parts in position to cause operation.

Fig. 29 is a front elevation of a detail of the board separating and returning part of the machine.

Fig. 30 is a plan view of the same.

Fig. 31 is a complete plan view of the board separating and returning mechanism.

Fig. 32 is a perspective view of the parts above line 32—32 of Fig. 31.

Fig. 33 is a sectional view similar to Fig. 26 but on a larger scale illustrating the operation of expelling heels and the boards which carry such heels.

Figs. 34 and 35 are cross sectional views of the board delivery means showing a heel board in position thereon in the act of being returned to the operator.

The same reference characters designate the same parts in all the figures.

In the following description I will for the sake of brevity designate the articles which are treated or dealt with in this machine as heels, instead of using a more cumbersome, although more accurate, term to designate that such articles are not finished heels or even merchantable heel blanks. It will be understood that as here used the term "heel" includes the collection or pile of lifts with intermediate layers or films of adhesive, just as they are assembled or built by the heel building operator. Such heels may or may not contain one or more nails to hold the lifts in alinement while they remain on the receiving board and before they have been put under pressure in the press.

The term "board" as herein used is intended to include any sort of plate, tray or the like having an extended surface capable of supporting heels side by side or in rows. The trays or plates used for this purpose are generally made of wood and are called boards, probably for that reason, although they are not always simply flat boards. Under the foregoing definition it will be understood that the term "board" as used in the following specification and claims includes any holder of whatever form and whatever the material of which it is made, which is capable of supporting heels and of being placed in and acted upon by a press in substantially the manner hereinafter indicated.

The embodiment of the press herein shown comprises a base 1 from which rise four corner posts, all of which are designated by the numeral 2, and these posts are connected together and braced by horizontal transverse bars 3. Preferably these posts and bars are

of rolled steel, the posts being of an angle section and the transverse bars of channel section; but these are details of construction which may be modified without departure from the spirit of the invention.

Mounted on the base are posts 4—4 having bearings 5—5 in which is mounted a main shaft 6 carrying a worm 7 which meshes with a worm gear 8 on a transverse shaft 9 which is mounted in bearings 10—10 on posts 11—11 also secured to the base. The driving pulley 12 is supported loosely on the main shaft 6 and is rotated by a belt 13 from any convenient countershaft. The main shaft also carries a second pulley 14 which is fast thereon and drives a belt 15 for a purpose later explained.

On the ends of the shaft 9 are cranks 16—16 engaged with connecting rods 17—17 which are connected through wrist pins 18—18 with a table 21. Said table is shown in plan view Fig. 18. On two of its opposite edges are shoulders 22 each defining a guideway which receives a guide 23, the latter being a bar running parallel to the posts and connected to the transverse beams 3 by screws 25. There are two of the guides 23, one at each side, these being located in the narrower sides of the frame. In each of the intermediate and wider sides of the frame are mounted two guides 26—26, the function of which is primarily to guide and also apply frictional pressure to the heel carrying boards which are forced upward through the interior of the press frame by the movements of the table as will presently be described. For this reason the guides 26 and likewise the guides 23, which have like functions, are formed with broad flat surfaces on their inner sides which are adapted to bear against the edges of the heel carrying boards. The screws 25 which support these guides are threaded through the bars 3, as shown in Figs. 5 and 6, and their inner ends are reduced in diameter to provide projections 27 entering holes in the guides, and shoulders bearing on the outer sides of these guides. Thus the guides are supported and at the same time are capable of being adjusted in or out so as to apply pressure of any desired intensity against the edges of the heel boards for the purpose of creating such friction as will support the boards with the load of heels thereon. Preferably each of the transverse frame bars is provided with such screws and said bars are comparatively near together, whereby the guides may be locally adjusted at many points and the pressure exerted by them against the heel boards may thus be made substantially uniform at all points.

At the front of the machine, and approximately at the same level as the top of the table when in its lowered position is a shelf 28 (see Figs. 2 and 4) on which the heel

boards are placed while being filled with heels.

The press is preferably made in such dimensions that it can be set beside the position occupied by the operator who builds heels and between two operators at adjoining benches without interfering with the freedom of movement of either operator and without requiring the operators to be placed farther apart than is required in any event by the present common practice. Thereby it is made possible to provide a press beside each heel building operator in spaces which always exist in heel factories and for which there is no other present use. In other words, my press occupies only space which would otherwise be unavailed of and does not require any valuable space for its installation. Thus placing the press brings the shelf 28 beside the heel building operator conveniently for her to place the heels as they are made upon a board lying on this shelf.

The driving pulley 12 is constantly rotated by the belt 13, but the table 21 is only intermittently operated, wherefore the pulley 12 is mounted loosely and means are provided for coupling and uncoupling the same to and from the shaft. Any form of clutch suitable for the purpose and including clutches which are already in use in connection with intermittently acting machines may be used for this purpose, but I have provided a special means for performing this function in connection with a mechanism for throwing into operation the heel ejecting devices at the same time.

On the inner end of the pulley hub is a stud 29 at one side of the shaft 6, and the shaft carries a stud 30 at the same distance from its axis as the stud 29. The pulley is movably axially on the shaft 6 so as to cause these studs to interfere, as shown in Fig. 23, and also to bring one clear of the other, as shown in Fig. 21, whereby the pulley is respectively coupled to the shaft and uncoupled therefrom. The pulley is so moved for this purpose by a lever 31 pivoted at 32 to a bracket 33 secured to one of the corner posts, and carrying a stud 34 with roller 35 on it, as shown in Fig. 7, which enters a groove 36 in the outer hub of the pulley. A rod 37 (Fig. 20) is connected to a stud 38 on this arm and passes through the two corner posts at the adjacent side of the machine. A spring 380 presses against one of the posts and against a collar 39 clamped adjustably on the rod, thus pushing the rod toward arm 31 and tending to place this arm in the position shown in Fig. 20, wherein the coupling provided by the studs 29 and 30 is disconnected. Rod 37 moves freely endwise through the posts.

65 An upright operating rod 40 runs beside

the corner post 2 nearest to the free end of lever 31, being supported in brackets 41 upon said post. This rod 40 carries an operating handle 42 in a position easily accessible to the operator, and carries an arm 43 which is connected by a link 44 and a pivot pin 45 with the lever 31. Such lever rests on a guide bracket 46 which has a stop 47 at the outer side of arm 31 so as to arrest the latter when the coupling has been disconnected. The connection between arm 43 and link 44 is made by a pin 48 occupying a slot 49 in the link, which provides lost motion for a purpose presently to be explained.

The guide bracket 46 carries lugs supporting a pivot 50 on which are mounted two latches 51 and 52, of which the former has a toe portion 53 and the latter a toe portion 54 adapted to engage the outer side of the arm 31 when the latter is moved inward to couple the pulley with the shaft, thereby holding the pulley in the coupled condition. The toe 53 is somewhat farther from the stop 47 than is the toe 54, while the tail 52^a of the latch 52 extends farther inward than the tail 51^a of the latch 51. On the under side of the table 21 is secured a block 55 in which is mounted the upper end of a depending rod 56, the lower end 56^a of which is bent and extended horizontally so as to overlie the tail piece 52^a. Secured adjustably on the rod 56 is a pawl carrier 57, the same being formed as a block having a passage way in which the rod 56 is contained and carrying a set screw 58 adapted to bear on the rod to secure the pawl carrier. A pawl 59 is hung by a pivot pin 60 to the carrier block 57 and projects below the same directly in front of the part 56^a and in the same vertical plane with the latch 51, behind which it lies and below the tail part of which its lower end extends. This lower end is widened at its forward side to form a toe which is adapted to engage the tail 51^a and press down upon the same when the table descends from its raised position. This pawl is pressed forward by a spring 62 in the carrier block to the limit imposed by a stop 63 on the block. As the toe of the pawl passes the latch in the upward movement of the table its inclined toe wipes against the end of the latch tail 51^a and is retracted against the yielding resistance of spring 62, springing forward as soon as it has passed the tail into the position above the same.

It will now be appreciated that when the operator seizes the handle 42 and draws it outward the pulley shifting arm 31 is drawn inward. When said arm has been thus drawn inward far enough to couple the pulley with the shaft 6 the latch toe 53 which previously rested upon the arm 31 drops in front of the same, and holds it in

the coupling position. The lost motion provided by the pin 48 and slot 49 allows the handle to be returned to the normal position close to the frame. The shaft 6 is now 5 set in rotation and drives cranks 16 through the worm and wheel gearing so as first to raise the table 21 and then lower it. As the table rises it carries the latch operating finger 56^a away from the latch 52, allowing 10 the latter to drop with its toe 54 in front of the arm 31 and raises the pawl 59 above the tail part of latch 51. As the table descends by reason of the continued movement of the driving mechanism the pawl 15 59 first engages latch 51 and releases the same from the arm 31, which is then allowed to move outward until it is stopped by the latch toe 54, and as the pawl passes by the latch 51 the toe of the latter drops 20 upon the upper side of the arm 31. Continuing descent of the table brings the finger 56^a upon the latch tail 52^a and raises the toe 54, thereby releasing the arm 31 and allowing the same to be pushed out by the 25 spring 380 and to move the pulley into the uncoupled position. The mechanism then stops with the table in its lowest position and the finger 56^a resting on the latch 52. The two latches are provided in order that 30 one may secure the pulley shifting arm when the pulley is first coupled to the shaft, and that the other may release this arm when the cycle of the table is completed.

The mechanism hereinbefore described remains at rest in the position indicated in the drawings while the operator fills with heels a board resting on the shelf 28. When the board is filled the operator slips it from the shelf on to the table, the board in that 40 position being designated 64 and the heels upon it 65. When the table is raised the loaded board is lifted and forced between the guides 26—26 and 23—23 at the opposite sides of the frame. It will be noted 45 from Fig. 1 that the guides 26 at the forward side of the frame terminate above the space through which boards loaded with heels are passed to the table. The board is then held by the friction exerted by the 50 guides on its edges in the position indicated by 64^a, and when the table descends it leaves the board in that position. As a means for additionally securing the boards so placed, I provide latches 66—66 pivoted on the 55 outer sides of the guides 23—23, the latching parts of which pass through holes in these guides directly under the edges of the board 64^a, as shown in Figs. 8, 9 and 10. These latches are beveled so that they are 60 displaced by the rising board and they are acted upon by springs 67, as shown in Fig. 9, so as to be placed under the board as soon as the same has passed them.

Each successive board with its load of 65 heels is placed in the position last described,

and in reaching its position it displaces the boards previously placed there until a stack of boards loaded with heels completely filling the frame has been formed. This is the normal condition of the machine after 70 it has once been put in operation. Each new charge of heels raises the stack already in the press and at the same time the top-most layer of heels is discharged. I will now describe the means for automatically 75 discharging the top layer of heels, which works in connection with the mechanism already described for operating the table.

Near the top of the frame are mounted two horizontal projecting beams 68 carrying a cross rod 69 near their outer ends, and on this cross rod is pivotally mounted a frame consisting of side bars 70 and a plate 71 to the edges of which are secured the bars 70. One side of this plate extends 80 substantially the whole length of the frame and forms a shelf 71^a, while the other side is cut short to leave an opening somewhat longer than the length of the heel boards. The second plate 72 is secured to the upper 90 side of the bars 70 and is provided with extensions 72^a which extend over and rest upon the topmost heel board, which is designated in the drawings as 64^b. The space between the plates 71 and 72 is enough 95 wider than the thickness of the boards to enable the latter to pass freely between them. The function of the plate 70 with its extensions 72^a is to support the inner 100 and freely swinging end of the pivoted frame 100 in line with the topmost heel board so that such board when it is discharged will pass over the plate 71. This function is capable of being performed by any extensions equivalent to the extensions 72^a. It is not 105 essential that the plate 72 extend entirely across the swinging frame, and I may omit that portion of said plate if desired. The feature to which I direct attention at this point is, however, that this frame has projections which overlie and bear on the top-most heel board, and any projections or supports which perform essentially the same function and accomplish essentially the same results is within the scope of this part 110 of my invention. The inner termination of the bottom plate 71 of this frame is outside of the press frame. This movable frame, the purpose of which is to receive the ejected heel boards, may be called the board guide. 115 After the board has been passed into it by the means presently to be described, it is supported and prevented from falling by a stop consisting of a cross bar 73 attached to and passing under the beams 68 and carrying adjustable set screws 74 beneath the bottom plate 71 and projecting toward the latter.

At the side of the press frame is an inclined runway 75 hung at one end from the 130

- outer end of one of the beams 68 and secured at its other end to the main press frame. This runway is adapted to return the ejected heel boards to the operator. Guides 76, 77, which are downwardly and forwardly inclined pass from the side of the board guiding frame under the shelf 71^a to the inner side of the runway 73, and rising from the outer side of the runway are guard posts 78, 79 and a guard rail 80. When the heel board passes the outer end of the bottom plate 71 its forward side is unsupported, while its rear side is supported by the shelf 71^a, and it is then tipped off, as indicated in Fig. 35, until it rests on the guides 76 and 77 and is conducted by the latter to the runway 75, down which it slides until arrested by an end stop 81 beside the operator's position and above the shelf 28.

Beneath the opening between the main press frame and the inner edge of the board guide is a chute 82 arranged so as to guide the discharged heels into a cage or bin 83 mounted at the right hand side of the machine, as shown in Fig. 1. When the top-most board is ejected into the board guide, the load of heels on the board next below, which is indicated as 64^c in the drawings, is ejected into the bin 83.

The means for thus ejecting the heels and heel boards comprises a pusher 84, which is conveniently made as an arm hung by a pivot 85 from a bar 86, which is adapted to slide back and forth and is provided with a rack 87 for driving it. This bar 86 is supported so as to move endwise in guides 88 on the under side of a top plate 89 secured to the top ends of the corner posts 2. The pusher 84 inclines toward the stack of heels and is widened at its inner end so as to bear on a considerable extent of the edge of the uppermost heel board, and from this end is hung a cleat 90 extending across all the rows of heels on the board 64^c next below the top board. This pusher is adjustable by means of a stop screw 91 bearing on the under side of the slide 86 so as to bring its pushing end and the cleat 90 into the planes of the board and heels which they are respectively intended to engage. The slide and pusher are normally held in the position shown in the drawings by a weight 92 arranged in vertical guideways 93 on the left hand side of the frame and hung by a flexible line 94 which passes over the pulley 95 on the top of the frame to a post 96 rising from the slide 86 in front of the top plate 89. The post 96 bearing against the edge of the plate is a stop to limit the outward movement of the slide and pusher. Directly above and in the same plane with the weight is a bar 97 (see Fig. 14) hung upon studs 98 which pass through slots 99 in the bar and are secured to the frame. A spring 100 is connected to this bar and to the frame

so as to exert a downward pull on the latter. The function of this spring and bar is to exert an initial starting impulse on the weight in order to retract the pusher quickly after the same has been advanced in expelling the board and heels, the weight being at that time raised and pressing upon the bar so as to raise the same and distort the spring. 70

To operate the slide and pusher there is provided a pinion 101 meshing with the rack 87 and loosely mounted on a shaft 102 which carries a pulley 103, around which passes the belt 15 previously described which is driven by the pulley 14 on the main shaft 6. 75 A clutch 104 is splined on shaft 102 and is adapted to be brought into and out of connection with a complementary clutching element associated with the pinion 101. These clutching elements in the form of invention here shown are studs 105, 106 eccentrically mounted on the clutch member 104 and on the pinion respectively at the same distance from the axis of shaft 102 (see Figs. 2 and 14). The clutch shifter is a lever 107, pivoted by a pin 108 on the top plate 89, one arm of which carries a stud 109 entering a groove in the clutch member 104. The other arm of said shifter lever extends beyond the left hand side of the frame and is there connected with a link 110, which latter is connected to an arm 111 on the controller rod 40. The connection between the shifter lever 107 and the link 110, being by means of a pin 112 on the lever and a slot 113 in the link, provides lost motion, permitting the controller to be returned to normal position after coupling with the clutch. The spring 114 is engaged with the shifter lever 107 and normally holds the latter against a stop 115 affixed to the top plate. There is also a latch arm 116 mounted by a pivot pin 117 on the top plate and held by a spring 118 yieldingly against a stop shoulder 119 on the shifter lever. The movement of the shifter lever which connects the clutch carries this shoulder past the shoulder 120 of the latch, which latter is caused by its spring to pass in front of the stop 119 and so hold the clutch shifter in the position for connecting the clutch, which is that shown in Figs. 16 and 28. A finger 121 is mounted on that part of the slide 86 which projects to the left of the frame, in the same plane with the latch 116 and therefore adapted to strike and displace said latch when the slide reaches the limit of its intended motion. 120

It will now be understood that when the operator moves the control handle 42 so as to set the table 21 in motion, the pinion 101 is 125 at the same time clutched to the shaft 102, which is set in motion simultaneously with the main shaft 6 by the pulley 14, belt 15 and pulley 103. Then while the table commences to rise the ejecting pusher is pro- 130

5 pelled toward the outlet, displacing the top-most board 64^b into the delivery guide therefor and ejecting the heels from the next lower board 64^c over the chute 82 into the bin 83. In case any of the heels should be stuck by an excess of the adhesive to the under side of the topmost board, as shown in Fig. 33, they are dislodged by a scraper 122 over which the board travels with its 10 under surface close to the edge thereof. This scraper may be the edge of the plate 71 or an independent knife attached to the side bars 70 in the same plane with the plate 71. When the pusher has reached the end of its 15 movement, the finger 121 displaces the latch 116 and allows the spring 114 to return the clutch shifter 107 so as to uncouple the pinion 101. The stretched spring 100 then gives the slide an initial returning impulse, 20 which is continued by the weight 92 until the pusher has returned to the normal position. As the motion of the table is slow, being derived through a worm and wheel gear, while the movement of the pusher is 25 rapid, the topmost board and the top layer of heels are ejected before the stack has been raised by the upward movement of the table to any appreciable extent.

30 In the foregoing description the side of the apparatus which is placed toward the position occupied by the operator when building heels has been considered as the front, and the directions left and right have been used with reference to the position of a person facing the front of the machine as thus defined. These terms indicating direction have been used for convenience of description solely and without intent to limit the invention to the precise 35 construction and arrangement of the apparatus herein shown in any other manner than as required by the express terms of the appended claims.

40 The machine thus described is automatic to the extent that it automatically applies pressure to the heels, automatically ejects heels from the press after they have remained long enough for the adhesive to become set, and automatically returns the 45 empty boards to the operator ready to be filled again. Thus it makes unnecessary the services of attendants to collect filled boards and return empty ones to the operator. It applies uniform pressure to all the heels, 50 this pressure being that necessary to overcome the friction of the entire stack of boards in the guides plus the weight of the collection of boards and heels. This pressure is applied in the first instance by the 55 table which rises beneath the stack and causes the collection of heels which it carries to bear the entire load above the stack plus such friction, and once applied the pressure is maintained by the friction between the board and the guides. The pres-

sure is continually renewed by the successive impulses applied to the stack every time a newly loaded board is added to the bottom of the pile, whereby the shrinkage of the heels in drying is continually and 70 automatically compensated for.

The heels are put under pressure almost as soon as built, that is, as soon as the operator has built enough heels to fill one board. Thus the time which elapses after 75 the first heel on the board has been built before the board is filled and the whole put under pressure is on the average in the neighborhood of eighteen minutes. Whatever the time may be, however, it is evidently only a small fraction of the time required to fill from two to six boards, that is, of the time usually elapsing under the present method before a heel is put in the press. Thus the cement or adhesive has not had 80 time to set before the heel is put in the press. In this description I have assumed that a slow drying paste is used, pastes of this type being the sort most generally used in heel factories and being preferable for various 85 reasons to the newer quick drying pastes. Once in the press the heels are maintained under uniform pressure for a long enough time to enable the adhesive to become firmly set. As an indication of what this time 90 would commonly be, I would say that the machines which I have built have capacity for a stack of from thirty to sixty filled boards, according to the height of heel being made. Assuming that the heels are so 95 high that only thirty boards are accommodated and that it requires the operator eighteen minutes to fill each board, it will be seen that a total time of nine hours at the least is required to fill the entire press. That is the time required for any one filled 100 board to pass from the entrance of the press at the bottom of the stack to the outlet at the top, and during all that time the heels remain under pressure. Then after being ejected from the press the heels are retained in the bin until the latter is filled and there they are further dried, wherefore by the time the heels are finally taken from the bin they are so thoroughly dried that they may 105 be taken directly to the heel compressing machines without having first to be left in the drying room.

The time and labor required under the old method for stacking up heels in the press and taking down a stack and sorting out the heels and boards is wholly eliminated with this machine, wherein each tier of heels is put under pressure singly and ejected singly without loss of time.

110 The operation of the machine imposes no additional labor upon the operator, who is able to place heels on the board supported upon the shelf 28 as easily as she can place them on boards arranged in the ordinary 115 120 125 130

way, more easily in fact. In order to put the heels under pressure all that the operator need do is to slide the board from the shelf over on the table 21 and then pull out 5 and let go the handle 42, returning immediately to her task of building heels, the work of applying pressure being then performed by power.

The term "table", as used in the foregoing description and in the claims, has no limiting significance other than as indicated by the description of its purpose and function. Since the table here shown is designed not only to support boards loaded 10 with heels, but also to place such loaded boards in the stack with others, and to apply the pressure under which the heels are confined while drying, it is in effect a trans- 15 ferrer and a pressure-applying pusher, therefore the descriptive term by which it is 20 designated includes any device, however constructed and arranged, which exercises transferring or pressure applying functions, and is to be so construed.

25 What I claim and desire to secure by Letters Patent is:—

1. A heel press adapted to support a stack 30 of boards with heels thereon and having provision for placing such boards at one end of the stack, means for exerting pressure endwise of the stack to the board last placed, and provisions for removing boards and heels from the opposite end of the stack.

2. A heel press comprising a frame having 35 friction causing guides adapted to engage the edges of heel boards, means for forcing boards loaded with heels between said guides and thereby displacing the boards and heels already between the guides, and means for ejecting boards and heels 40 from the end of the stack opposite to that at which such pressure is so applied.

3. An automatic heel press comprising 45 guides surrounding a space adapted to receive boards loaded with heels and to press firmly against the edges of boards inserted there into, a pressure applying plate or table movable back and forth in line with said space, an inlet for admitting loaded boards 50 between said table and the entrance end of said space, mechanism for actuating said table and an outlet from said space from which the boards and heels are separately removed.

55 4. A heel pressing apparatus comprising a frame adapted to contain a stack of boards with heels loaded thereon, means for receiving, and applying pressure to, boards charged with heels inserted individually in 60 said press, and means for removing pressed and dried heels individually from said press.

5. A heel pressing apparatus comprising 65 a frame adapted to contain a series of heel carrying trays loaded with newly built heels, means for exerting friction-causing pres-

sure against the trays in said frame to resist movement of the trays, means for adding a loaded tray at one end of said series and for applying pressure through the same sufficient to move the series against such 70 frictional resistance, and means for automatically removing boards and heels from the opposite end of said series.

6. A heel pressing apparatus comprising a frame adapted to contain a series of heel 75 carrying trays loaded with newly built heels, means for exerting friction-causing pressure against the trays in said frame to resist movement of the trays, means for adding a loaded tray at one end of said series and 80 for applying pressure through the same sufficient to move the series against such frictional resistance, means for automatically removing boards and heels from the opposite end of said series, and means for automatically separating the boards and the heels so removed from one another.

7. A heel pressing apparatus comprising a frame adapted to contain a series of heel carrying trays loaded with newly built 90 heels, means for exerting friction-causing pressure against the trays in said frame to resist movement of the trays, means for adding a loaded tray at one end of said series and for applying pressure through the same 95 sufficient to move the series against such frictional resistance, means for automatically removing boards and heels from the opposite end of said series, and automatic means for separating the boards from the 100 heels so removed and returning such boards to the operator.

8. An apparatus for pressing newly constructed heels comprising a frame adapted 105 to receive boards or trays loaded with heels and to confine the same in such manner that the heels are held under pressure but the loaded boards are also movable from one end of the press to the other, said press having an inlet in which boards loaded 110 with heels may be placed from time to time, and means for applying pressure to the boards so inserted and at the same time propelling the collection of boards and heels toward the outlet.

115 9. A heel pressing apparatus comprising means for holding a stack of boards loaded with heels, having an inlet for admission of such boards at one end of the stack and an outlet for ejection of boards and heels at the other end of the stack, means for pressing upon the board inserted through such inlet and thereby shifting the entire stack toward the outlet, an ejector arranged to expel the topmost board and the adjacent tier of heels from such stack, and a common controlled means for setting said pressure applying means and said ejector in operation.

120 10. A heel press adapted to contain a 130

stack of heels under pressure having an inlet through which boards loaded with heels may be singly admitted and having an outlet, in combination with means for applying pressure from time to time to said stack in a direction toward such outlet.

11. In a heel press having provision for containing a stack of boards or trays with heels upon and between such boards, a guide located at one side of said press through which the endmost board of such stack is adapted to pass, and means for expelling such board from the stack into said guide.

15 12. In a heel press having means for containing a stack of boards or trays with heels loaded thereon and an outlet adjacent to one end of said stack, means for expelling the endmost board and the contiguous tier 20 of heels through such outlet, a receptacle for heels so expelled, and a guide arranged to conduct boards so expelled over said receptacle.

13. A heel press adapted to contain a stack of boards loaded with heels having an inlet for such boards at one end and a lateral outlet at the opposite end of the stack, means for applying pressure to such boards and heels and intermittently propelling the stack from said inlet toward said outlet, an ejector for expelling the endmost board and the adjacent tier of heels through such outlet, and guiding means arranged adjacent to the outlet for receiving 35 the boards so expelled and returning such boards to a point near said inlet.

14. A heel press comprising an upright frame having a support adapted to receive a stack of boards and heels supported on such boards, said frame having an inlet at one side, means for supporting the stack above said inlet whereby boards may be passed through the inlet below the stack, a table normally arranged below said inlet 45 to receive boards passed therethrough, and means for moving said table so as to transfer the board so placed to the stack and at the same time apply pressure through such board to the stack.

50 15. A heel press comprising an upright frame having an inlet at one side, means within the frame above the inlet adapted to receive a stack of boards loaded with heels and constructed to apply friction-causing pressure to opposite edges of said boards whereby to hold such stack and yieldingly resist movement thereof through the frame, a support outside the frame at the level of the inlet on which a board is placed while 55 being loaded, a table within the frame normally held in such a position that a loaded board may be readily placed upon it by being passed from said support through the inlet, and automatic mechanism under the 60 control of the operator for raising said

table with the loaded board thereon into the stack holding part of the frame.

16. A heel press comprising a frame having an open interior adapted to contain a stack of boards loaded with heels, guide 70 members extending longitudinally of said space on opposite sides thereof, means for adjusting said members inwardly with respect to said space whereby to exert pressure against the edges of such boards contained therein, means for propelling such stack of boards through such space, an ejector arranged to move across one end of said space for expelling boards and heels therefrom, and a common controlling mechanism for setting said ejecting means and said propelling means in conjoint operation.

17. In an apparatus for pressing heels in combination with means adapted to contain 85 a stack of boards loaded with heels and maintain the same under pressure, and a pressure applying apparatus arranged to add such boards from time to time to such stack at one end thereof and at the same 90 time advance such stack, a pusher laterally movable across the advancing end of the stack having means to engage the endmost board and the tier of heels adjacent thereto, mechanism operating said pusher including 95 a manually connectible clutch, means associated with said pusher for disconnecting the clutch, and a potentially active retracting means for returning said pusher upon disconnection of the clutch.

18. In an apparatus for pressing heels in combination with means adapted to contain a stack of boards loaded with heels and maintain the same under pressure, and a pressure applying apparatus arranged to 105 add such boards from time to time to such stack at one end thereof and at the same time advance such stack, a pusher laterally movable across the advancing end of the stack having means to engage the endmost 110 board and the tier of heels adjacent thereto, mechanism operating said pusher including a manually connectible clutch, means associated with said pusher for disconnecting the clutch, and a potentially active retracting 115 means for returning said pusher upon disconnection of the clutch, said retracting means comprising a weight and a spring arranged to press downwardly on said weight when the latter is in the position occupied 120 at the time of disconnection of said clutch.

19. In a press apparatus having provisions for containing a stack of boards loaded with heels and means for propelling such stack, and having an outlet at the side of one end 125 of said stack, a movably mounted guide adapted to admit one of said boards, and means for expelling the endmost board of the stack into such guide, the guide being movable and having an extension overlying 130

the stack and adapted to be engaged by the endmost board, whereby it is automatically registered with such board.

20. In a press apparatus having provisions 5 for containing a stack of boards loaded with heels and means for propelling such stack, and having an outlet at the side of one end of said stack, a movably mounted guide adapted to admit one of said boards, and 10 means for expelling the endmost board of the stack into such guide, such guide having an opening at one side at a distance from the stack and a supporting shelf at the opposite side, whereby a board propelled 15 through the guide is tipped therefrom through said opening.

21. In a press apparatus having provisions for containing a stack of boards loaded with heels and means for propelling such stack, 20 and having an outlet at the side of one end of said stack, a movably mounted guide adapted to admit one of said boards, and means for expelling the endmost board of the stack into such guide, said guide having 25 means for supporting the opposite edges of the boards and one of said means terminating short of the other, whereby the board after passing such termination is supported at one edge only and is thereby caused to 30 fall from the guide.

22. In a press apparatus having provisions for containing a stack of boards loaded with heels and means for propelling such stack, and having an outlet at the side of one end 35 of said stack, a movably mounted guide adapted to admit one of said boards, and means for expelling the endmost board of the stack into such guide, said guide having means for supporting the opposite edges of 40 the boards and one of said means terminating short of the other, whereby the board after passing such termination is supported at one edge only and is thereby caused to fall from the guide, and conducting means 45 to which such board is thereby delivered and by which the same is carried to the desired location.

23. A heel press comprising an upright frame adapted to be placed beside the working position of a heel building operator, said 50 frame having an inlet at the side next to such position and providing a space above said inlet wherein a stack of boards loaded with heels may be contained, means extending laterally from the upper part of the frame, a guide adapted to receive boards supported by said means, and a runway extending from said guide to a point convenient to such operator's position.

24. A heel press comprising an upright frame adapted to be placed beside the working position of a heel building operator, said 60 frame having an inlet at the side next to such position and providing a space above 65 said inlet wherein a stack of boards loaded

with heels may be contained, means extending laterally from the upper part of the frame, a guide adapted to receive boards supported by said means, and a runway extending from said guide to a point convenient to such operator's position, said guide having provisions for receiving a board from the end of the stack which is contained in the frame and also having provisions for discharging such board into said 75 runway.

25. A heel press comprising an upright frame adapted to be placed beside the working position of a heel building operator, said frame having an inlet at the side next to 80 such position and providing a space above said inlet wherein a stack of boards loaded with heels may be contained, means extending laterally from the upper part of the frame, a guide adapted to receive boards 85 supported by said means, and a runway extending from said guide to a point convenient to such operator's position, and means for displacing the endmost boards of the stack successively into said guide and 90 through the same to said runway.

26. In a heel press having a space adapted to receive boards loaded with heels and having an inlet adjacent to one end of said space and an outlet adjacent to the opposite end thereof, a reciprocating pusher for receiving boards loaded with heels, transferring such boards into said space, and pushing boards already therein toward said outlet, an ejector movable back and forth 100 across said space toward and from said outlet, a drive shaft for actuating said pusher, a drive shaft for actuating said ejector, one of said shafts being driven by the other, a disconnectible clutch for causing said drive shaft to be put into and out of operation, a disconnectible clutch between the second shaft and the ejector, and common controlling means for connecting both clutches simultaneously.

27. The combination with a shaft, a driving element therefor and a disconnectible clutch between said shaft and driving element, of a clutch shifter, a reciprocating table driven by said shaft, and two 115 latches for holding said shifter in clutch coupling position, one of said latches being operative for that purpose when the table is in one position and the other being so operative when the table is in another position, 120 both latches being rendered alternately operative and inoperative by the table.

28. The combination of a reciprocating table, of a shaft for driving the same, a driving element for the shaft, a clutch for 125 connecting said element with the shaft and disconnecting it therefrom, a clutch shifter for connecting and disconnecting said clutch, two latches each adapted to hold the clutch shifter in position for connecting the clutch, 130

means carried by the table for disconnecting one of said latches when the table is in its normal position of rest, and means carried by the table for first displacing and then 5 releasing the other latch when the table is in motion in a different position.

29. The combination with a reciprocating table, of a shaft for driving the same, a driving element for the shaft, a clutch for connecting said element with the shaft and disconnecting it therefrom, a clutch shifter for connecting and disconnecting said clutch, two 10 latches each adapted to hold the clutch shifter

in position for connecting the clutch, means carried by the table for disconnecting one of 15 said latches when the table is in its normal position of rest, and means carried by the table for first displacing and then releasing the other latch when the table is in motion in a different position, the second named latch 20 being located so that it leaves the clutch shifter free after having been displaced and released by the table.

In testimony whereof I have affixed my signature.

EDWIN HANSALPAKAR.
